UPHOLSTERY SPRING CONSTRUCTION

Emanuel Samel, Denville, N. J.

Application August 21, 1947, Serial No. 769,891

6 Claims. (Cl. 5—248)

1

My present invention relates to an upholstery spring construction and a method of assembling such structures into an upholstery assembly such as is used for the bottoms and other portions of upholstered furniture.

It has been customary for many years to use substantially helical springs in making up upholstered furniture, these springs usually having a somewhat smaller diameter intermediate their ends than at the ends thereof, although this is relatively immaterial from the point of view of the present invention. In assembling such springs into an article of furniture it is customary, for example, in making a chair or sofa bottom or seat, first to build a frame of some rigid material, such as wood, then to support the lower ends of the springs to form the seat, or the rear ends when a back is being formed, to the lower or rear face of the frame by the use of webbing, usually arranged in bands secured at their ends to the frame and sewed together and to the lowermost or rearmost ends of the springs by strong thread or cord. Other arrangements equivalent thereto from the present point of view have been suggested for securing the rear or lowermost ends of the springs to the frame and for locating the springs with their axes all substantially parallel and in a desired distribution pattern.

The upper or forward ends of the springs have customarily been connected together and to the uppermost or forward parts of the frame by the use of quite heavy cord, which is usually in accordance with prior art practices, cut into suitable lengths, then one end is secured to a part of the frame in the forming of a single pass. The cord is then extended to the nearest spring to be connected in this pass and a knot made between the cord and the endmost or some other turn of the spring adjacent to the end, this knot being made non-slipping as to the cord by pulling the end of the cord through a loop in forming one or two half hitches or some other similar type of knot. The cord has then customarily been extended across the spring and then been connected to a turn substantially diametrically opposite the first point of connection by a similar knot. In like manner the cord is attached to each spring in a row and then the other end finally attached to the frame opposite the point of attachment of the first-named end.

In carrying out this operation it is necessary first to cut off suitable lengths of cord from a supply of an indefinite length upon a reel or other suitable dispensing package, then, in making each knot, to pull the free end through a loop one or

2

more times. The knot, after having been formed may be non-slipping as to the cord, but can and does during subsequent use move endways as to the wire of the spring. The whole operation in forming a chair or sofa bottom is tiresome and time-consuming in the extreme.

An object of the present invention is to save a large part of the time involved in upholstery spring assembly in accordance with the prior art method as above outlined and to provide a better finished product than has been possible by the use of prior art methods and structures as aforesaid. To this end it is a specific object of the present invention to provide a plurality of irregularly shaped portions on the endmost coil and possibly also on at least one other coil adjacent to the endmost coil, to which a bight of the cord may be suitably connected without the necessity of pulling an end through a loop in forming a knot which will be non-slipping as to the cord. At the same time, the provision of this irregularly shaped portion, which is rigid with the wire of the spring, will insure that any knot made in accordance with the present invention and by the use of such an irregular portion will be non-slipping as to the spring.

Further and more detailed objects of the present invention in this respect comprise particular embodiments of the invention as to the shape and construction of the irregularly shaped portions and including the making of such portions from parts of the spring wire bent up into suitable shape, preferably generally in the form of the letter T, or the making of such portions from one or more separate parts, suitably rigidly secured, as by welding, to the spring itself.

A further object of the present invention is to provide a spring assembly formed by the use of springs made in accordance with the present invention and connected by cords which are extended in a plurality of passes, preferably substantially at right angles to one another, so that each spring is connected in at least two passes as aforesaid, whereby to prevent the dislocation of the springs in the plane of the upper or forward ends thereof out of the desired distribution pattern in any direction in such plane. This result may be further insured by providing not only two sets of passes of cord at right angles to one another, and which are usually parallel to the sides of a rectangular frame in which the spring assembly is secured, but also by providing two additional sets of diagonally disposed passes of cord similarly connected to the frame and to the springs.

55 A further detailed object of the present invention

tion is to provide for the making of one or more or all the passes from a single length of cord prior to the severance of the length being employed from a supply body of cord of indefinite length. In this way the use of cord is minimized as it is unnecessary first to cut off individual lengths and to waste any substantial amount of the cord in so doing.

A further principal object of the present invention is to provide a method of spring assembly in accordance with the present invention and using the springs of the present invention to make a structure as outlined above.

While it is recognized that springs in accordance with the present invention may be slightly more expensive to make than are the conventional upholstery springs due to the necessity of forming or fabricating the irregular portions on at least one end coil thereof, the savings in time and hence in labor cost in the manufacture of the final articles of furniture are so great as far to outweigh the slightly increased cost of the novel springs.

Further and more detailed objects of the present invention will become apparent from the following specification and appended claims, when considered in connection with the accompanying drawings, in which:

Figure 1 is a view principally in perspective and with parts broken away showing a part of a spring assembly made in accordance with the present invention;

Fig. 2 is a diagrammatic plan view of an assembly in accordance with the present invention; and

Figs. 3, 4 and 5 are fragmentary detailed views, principally in plan, illustrating modified forms of irregular cord-attachment portions in accordance with the present invention.

Consider first the spring as a separate article and the irregularly shaped portions as above generally described formed or secured thereon. Referring first to the form of the invention shown in Fig. 1, there is illustrated but two springs 1 which are in the form of conventional upholstery springs, with the exception of the irregular portions thereof in accordance with the present invention. These portions are disposed principally, if not solely, on the endmost turn or coil of the spring shown at 2. Preferably there are at least four such irregularly shaped portions formed by or on the endmost turn and substantially equiangularly disposed about this turn. In accordance with the form shown in Fig. 1, these portions each comprise a bar 3, which may be formed from a piece of the same type of wire of which the spring 1 is formed, or may be some other suitable material and fabricated in any desired manner, the use of spring metal not being essential in the construction of these parts. As shown, there is a simple bar 3, which is suitably secured as by welding to a part of the uppermost turn 2 intermediate the ends of the bar 3. This provides two projections 4 and 5 to which connection may be made by a cord as hereinafter more particularly set forth. It is also contemplated, however, that any suitable means of securing an irregularly-shaped portion to a part of the spring proper may be used as the equivalent of welding, for example, means such as a set screw or clamp or clip, as will appear from the foregoing to those skilled in the art, the purpose being that the irregularly shaped portion be suitably rigidly secured to the main body of the spring, which in turn may be formed in any conventional manner.

It is preferred that the irregular portion, such as the bars 3, be secured to the turn 2 of the spring on the underside, as seen in Fig. 1 so as to be within the axial dimensions of the spring, considered apart from the irregularly shaped portions per se. In this way the portions provided in accordance with the present invention do not interfere with the final product and do not project in a direction such as to damage any upholstery material which may be used in conjunction therewith. The connection of the cord to the bars or portions will be described hereinafter.

Considering now the embodiments of the invention shown in Figs. 3 and 4, it will be noted that the irregularly shaped portions generally indicated respectively at 6 and 7 are formed from integral parts of the uppermost turn 2 of the spring by bending the wire thereof into peculiar and desired shapes. In general, the shapes in these two figures is that of the outlines of the letter T, this shape being in effect secured at the end of the stem of the T to the center or bottom of the bight of a portion of the wire shaped as the letter U, which is formed with a center or bight portion indicated at 8 and sides indicated at 9.

Referring now particularly to the Fig. 3 form of the invention, the part forming the outline of the letter T includes the side portions 10 defining the stem of the T, portions 11 defining the upper side of the cross part or top of the T, and the central portion 12 which is in the form of a reentrant part extending from the center of the top of the T downwardly into the stem thereof, as shown. The top portions 11 are connected to side portions 10 by end portions 13 and those in turn by acute angled portions 14 extending from the side portions 10 as shown. The center part 12 has a part circular recess defining portion at the inner end thereof. This form results in a very effective construction in that it is easy to connect a cord thereto by winding it in substantially figure 8 form between the recess defined by parts 10 and 14 on one side, the center recess defined by the part 12 and the recess defined by parts 10 and 14 on the other side. This may be accomplished while maintaining the stretch of the cord between its points of attachment, for example, between springs or between adjacent parts of the same spring, in a taut condition and working always with a bight of the cord. In accordance with the present invention it has been found that a desired greater tautness is possible than according to prior art practices.

Referring now to the form of Fig. 4, there is illustrated a somewhat simpler form. In this form the center part is formed merely as the outline of the letter T, without any reentrant portion corresponding to 12 in Fig. 3. The wire is bent from the inner ends of the parts 8 forming the bight of the U upwardly as shown at 15 to form the stem of the T, thence outwardly as shown at 16 to form the underside of the T, thence around to form the upper side of the top of the T as shown at 17. Any type of knot or plural twist which may be formed with a bight of a cord may be effective in securing the cord to the irregular portion 7 of Fig. 4, the invention in this case not residing in any particular type of knot, many of which are known.

Referring now to the Fig. 5 form of the invention, there is illustrated an embodiment in which the irregular part is again secured to the bight 18 of a U formed of the principal part of the wire of the spring by bending it to form sides 19 of the U and the bight 18 thereof, as

shown. Centrally of the bight of the U there is secured thereto, as by welding, one or more separate pieces formed as in the shape of the letter T and including a stem portion 20 and a top portion or bar 21. The cord may be suitably secured about these portions in a manner which will be obvious to those skilled in the art and who are acquainted with the making of knots.

It is noted that in all the forms of Figs. 3, 4 and 5, the irregularly shaped portion is formed in one single plane which is substantially the plane of the top coil of the spring; that the principal part of the irregularly shaped portion is in the form of the letter T or the outline thereof, and that it is connected centrally of the bight of a U-shaped portion of the turn 2 of the spring and in the plane thereof extending between the sides of the U.

Consider now the spring assembly as a construction and the method of making it. There is shown in Figs. 1 and 2 a frame including frame members 22 and 23, this frame being conventionally shown as a square, although it may be and usually is in some rectangular form. On the other hand, the invention is not limited to any particular form of the frame as it may be adaptable to any such form made of any suitable rigid material, usually wood, in which a plurality of springs are arranged according to a predetermined distribution pattern. In the usual course and as herein shown, this pattern includes a plurality of rows of springs which may be arranged as shown equidistant in both dimensions or at the corners of squares, as to the center lines of the springs. In the usual course, the axes of these springs are all parallel to one another and are perpendicular to the general plane of the frame. In accordance with prior art practice, or in accordance with any desired practice or construction, the lower or rear ends of the springs may be connected together and to the frame by any suitable means here generally indicated as strips of webbing 24, Fig. 1, which are usually arranged at right angles to one another, secured at their ends to the frame in any suitable manner, and secured to the lower or rear ends of each of the springs in any desired manner, for example, by sewing them with a strong thread using a curved needle. Any desired means for supporting the lower or rear ends of the springs to the frame may be used in accordance with the present invention, which is restricted to the provision of the irregular portions as above described, to the construction of the spring assembly using springs provided with such irregular portions and to the method of making such an assembly.

Referring now particularly to Fig. 2, there is shown a plurality of springs 25, 26, 27, 28 forming one row and shown horizontal in this figure, which are connected together by a length of cord anchored as shown at 29 to the frame 22 on the left and secured to each of the springs 25 to 28, inclusive, then anchored at its other end to the other frame 22, as shown at 30. Thus, the pass of the cord from point 29 to the point 30 connecting the springs 25 to 28 may be considered one single pass. If desired, the cord may be terminated at a point 39 and a separate length of cord may be extended from the point 31 to secure the springs 32, 33, 34 and 35 and connected again to the point 36. Alternatively, the cord may be extended from the point 30 to the point 36 and then connected across to the point 31 including connections in series with the

springs 35 to 32 in this reverse sequence. In a similar manner, each of the springs in the entire assembly may be connected by passes of cord which are horizontal in this view. It is preferable and usual practice also to connect the springs together by passes of cord arranged at right angles to one another, thus there are shown passes of the cord indicated generally at 37, 38, 39 and 40 arranged in a vertical direction, as shown in Fig. 2 at right angles to the passes first described. If desired, two additional sets of passes arranged as diagonals may be used, each pass being connected at its ends to the frame members 22 and 23 and connected intermediate its ends to the springs which are in alignment with the passes respectively. Thus, the endmost diagonal passes may be connected to but one spring, as shown for the pass 41 which connects only to the spring 25 and is connected to the frame members 22 and 23 at points 42 and 43, respectively. The remainder of the diagonal passes may be connected similarly to those previously described and as will be obvious from an inspection of Fig. 2.

If desired, a single length of cord may be extended to include some or all the passes necessary to connect the springs in the manner shown in Fig. 2 prior to the cord used in forming the passes being severed from a supply body thereof of indefinite length, such as a reel of cord. When this is done, however, it is preferred that the termini of each pass of cord be rigidly secured to the frame in any suitable manner as by a tack or nail.

In accordance with the present invention and as best seen on an enlarged scale in Fig. 1, the cord here shown at 44 may be connected as indicated at 45 as by a suitable nail to the frame member 22. It is sometimes desired that the endmost spring in a row, such as the row of springs 25 to 28, shown in Fig. 2, be connected somewhat differently to the cord than the intermediate springs of that row. This different connection is shown in detail in Fig. 1 and includes the provision of a connection between the cord and a turn of the spring below but adjacent to the outermost or uppermost turn 2 thereof. For this purpose the spring in accordance with the present invention is provided on such adjacent turn as the turn 46 with an irregularly shaped portion 47 as shown. The portion 47 may be exactly the same as the portion 3 above described or may take any of the forms of Figs. 3 to 5, or any equivalent thereof. The cord 44 is extended in a taut manner to the irregular portion 47, then suitably knotted thereto by a knot which may be formed from a bight of the cord. The cord is then extended in a plane diametrically across the spring 4 as shown at 48 to connect to an irregularly shaped portion shown at 49 by a similar knot. The cord then extends rearwardly across the spring in a stretch shown at 50 to connect to a point substantially diametrically opposite the point 49 at 51, and is there connected thereto by a similar knot. The cord is then extended in a stretch 52 to connect to the next adjacent spring, which may be in the position of the spring 26, as shown in Fig. 2, it being understood that the spring shown at the left in Fig. 1 may be in a position corresponding to that shown at 25 in Fig. 2. Connection of the cord with the intermediate springs, such as those shown at 26 and 27 for the first horizontal pass in Fig. 2 between the points 29 and 30, or the springs 33 and 34 for the next horizontal pass between the points

31 and **36** in that figure is preferably made by connecting the cord to two substantially diametrically opposite portions of the uppermost turn, as shown at the points **53** and **54** between which the cord extends in a stretch **55**. The remainder of the connections may be made in a similar manner to that just described.

While "cord" is referred to throughout the present specification, the term is to be construed in a broad sense. It is also used to designate the material known in the upholstery art as "spring twine."

By the provision of the foregoing it will be seen that I have provided a novel spring construction, a novel spring assembly which may be made using the spring construction of the present invention, and a novel method of effecting such assembly using cord which may be anchored initially at one end and then employed in connecting the springs together without first severing any portion of the cord from the general supply body thereof and without tediously pulling any cord ends through a loop in forming any knot. The connections between the cord and the springs in each case is non-slipping endwise of either the cord or the wire of the spring to which it is connected, and the whole may be effected in a minimum of time by persons with relatively little training and experience, and with a maximum economy in the use of the cord.

While there is shown herein but a few of the possible embodiments of the invention, I do not wish to be limited except by the scope of the appended claims, which are to be construed validly as broadly as the state of the prior art permits.

I claim:

1. An upholstery spring having a plurality of coils and provided on one end coil with a plurality of irregularly shaped portions, each of said irregularly shaped portions comprising at least one separate part rigidly secured to the wire of said end coil of said spring and substantially equiangularly disposed about said end coil, each of said irregularly shaped portions being adapted to have a flexible cord knotted thereto by a knot formed from a bight portion of the cord, so that said cord will be prevented from movement with respect to said end coil of said spring by the rigid connection between said irregularly shaped portion and the end coil of said spring.

2. An upholstery spring in accordance with claim 1, wherein each of said irregularly shaped portions has at least a part thereof arranged substantially in the shape of the letter T.

3. An upholstery spring in accordance with claim 1 wherein each of said irregularly shaped portions is formed by a cross bar welded to the wire of one end coil of said spring on a side of said end coil toward the opposite end of said spring, so as to be inside the confines of the end coils of said spring in an axial direction, said cross bars extending at substantially right angles to the parts of the wire to which said cross bars are welded respectively.

4. An upholstery spring in accordance with

claim 1, wherein each of said irregularly shaped portions is formed by a separate member having the shape of the letter T rigidly secured at the end of the stem of the T to a part of the wire of said spring.

5. An upholstery spring assembly, comprising a plurality of coil springs disposed with their longitudinal axes substantially parallel and located according to a predetermined distribution pattern, a rigid frame, means carried by the frame for supporting one end of each of said springs in said distribution pattern, each of said springs having its other end provided with a plurality of irregular portions rigid therewith, and at least one flexible cord of non-metallic material secured to said frame and connected by non-slipping type knots, each formed on a bight of said cord to secure said cord to said irregular portions so as to hold the other ends of said springs against substantial dislocation out of said distribution pattern, while permitting the yielding of said springs during the subsequent use of said assembly.

6. An upholstery spring assembly in accordance with claim 5, wherein all of said springs are secured in said distribution pattern by a single length of cord connected at the ends of each of a plurality of straight line passes to said frame and connected to each of said springs in alignment with each of said passes respectively, said cord and its connections being effective to secure said springs against dislocation in any direction in a plane containing the ends of said spring to which said cord is connected, and said cord extending from one pass to another until said springs are connected as aforesaid, there being passes of said cord substantially at right angles to one another so that each of said springs is included in at least two passes which are respectively substantially at right angles to one another.

EMANUEL SAMEL.
